UNITED STATES PATENT OFFICE

JOSEPH FOLK, OF LA PORTE, INDIANA, ASSIGNOR TO U. S. SLICING MACHINE COMPANY, OF LA PORTE, INDIANA, A CORPORATION OF INDIANA

DESIGN FOR A SLICING MACHINE

Application filed February 16, 1933. Serial No. 47,233. Term of patent 14 years.

To all whom it may concern:

Be it known that I, JOSEPH FOLK, a citizen of the United States, residing at La Porte, in the county of La Porte and State of Indiana, have invented a new, original, and ornamental Design for a Slicing Machine, of which the following is a specification, reference being had to the accompanying drawings, forming part thereof.

Fig. 1 represents a side elevation of the slicing machine showing my new design;

Fig. 2 is another side elevation of the slicing machine viewed from the side of the slicing machine opposite to that illustrated in Fig. 1;

Fig. 3 is a plan view of the same; and

Fig. 4 is a rear elevation looking from the right in Fig. 1.

I claim:

The ornamental design for a slicing machine as shown.

JOSEPH FOLK.
